DESIGN FOR A BOX

Frank McIntosh, New York, N. Y., assignor to Letheric Incorporated, New York, N. Y., a corporation of New York

Application May 16, 1941, Serial No. 100,979

Term of patent 7 years

To all whom it may concern:

Be it known that I, Frank McIntosh, a citizen of the United States, residing at New York city, in the county of New York and State of New York, have invented a new, original, and ornamental Design for a Box, of which the following is a specification, reference being had to the accompanying drawing, forming part thereof.

In the drawing:

Fig. 1 is a top plan view of a box embodying my new design.

Fig. 2 is a side elevational view thereof.

The curled-edge horizontal band and the contrasting areas above and below it, as shown in Fig. 2, constitute a unit, three of which cover substantially the entire cylindrical wall of the box.

I claim:

The ornamental design for a box, substantially as shown and described.

FRANK McINTOSH.
